I.B. Hartwell

Door Spring

Received April 10, 1848

Des 4

Isaac B. Hartwell, Woodstock, Vermont.
Letters Patent, No 4. Dated April 10. 1843. —
The Schedule referred to in this Letters Patent and making part of the same.

To all whom it may concern: Be it known that I, Isaac B. Hartwell, of Woodstock, in the County of Windsor and State of Vermont, have designed and invented a new and original shape or configuration, of the apparatus for closing doors, by means of a spring, which apparatus is usually known under the name of a Door Spring; and I do hereby declare that the accompanying drawing is a clear and exact representation of the shape and configuration of my said apparatus. Fig. 1. shows the upper part of a door, and its frame, with the apparatus attached thereto. Fig. 2. is a top view of the same, with the door shown partially open. A, is the door, and B, the upper casing of the door frame. C, is a metallic ear or bracket, which is attached to the casing B; from this bracket rises a vertical pin D around which a spiral spring is to be coiled. This bracket and pin are shown separately in fig. 3. Over this pin is passed a lever E, which turns upon it as a fulcrum, around the pin D, a spiral spring F, is coiled, as shown in fig. 1. one end of this spring enters a hole made to receive it in the lever E, near to its fulcrum, and the other end enters a hole in the piece of metal G, which fits on to the upper end of the pin D, where it

is held in place by passing a small pin through it, and through the pin D. By turning the piece of metal G, in the manner of a screw nut, the torsion of the spiral spring may be regulated at pleasure.

H, is a friction roller which works on a vertical pin rising from a bracket I, attached to the door. The friction roller H, is grooved, in order to guide the edge of the lever E, and to cause said lever to turn steadily on the pin D. I usually solder a thin tube, one inch or two in length, into the hole which passes over said pin; the spiral spring F, embraces this thin tube, as it does the pin D. The shape and configuration of the lever E, is shown distinctly in fig. 2. The concave J, at its end receives the friction roller H, when the door is fully opened, and counteracts the action of the spring sufficiently to prevent its shutting without a slight degree of aid.

Having thus fully described the shape or configuration of my door spring or apparatus for the closing of doors, what I claim as constituting my invention or design, is the forming of the respective parts, and the connecting them with each other in such manner as that it shall, when completed, have the shape and configuration of that herein described and represented.
